DUAL COMBUSTION SYSTEM FOR COMBUSTION TUBE BURNERS

Filed Dec. 23, 1946

UNITED STATES PATENT OFFICE

2,447,211

DUAL COMBUSTION SYSTEM FOR COMBUSTION TUBE BURNERS

Edward Rousseau, Jewett City, Conn.

Application December 23, 1946, Serial No. 717,973

2 Claims. (Cl. 158—87)

1

This invention relates to improvements in liquid fuel burners of the type adapted for location in the fire box of a household range, water heater or the like.

The principal object of the invention is the provision of a liquid fuel burner which is arranged and adapted to operate on liquid hydrocarbon fuel and is constructed in the novel manner to operate efficiently and economically. The burner is adapted for use in the fire box of a household range but it may be used for various other purposes.

According to novel features of the invention, the burner includes a base having various channels and upwardly extending perforated sleeves arranged to provide inner and outer systems of cooperating components to the end that the systems are independently operable or may be operated simultaneously. If desired the inner system may be used as for heating the lid of a stove without the necessity of operating the outer system which is desirable when it is not necessary to employ the burner for space heating.

On the other hand, the outer system may be used when it is desired for space heating or to heat a water coil adjacent thereto for other purposes.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a sectional elevational view through a burner embodying the novel features of the invention; and

Fig. 2 is a sectional plan view on the line 2—2 of Fig. 1 with certain rings or caps omitted for clearness.

Referring now to the drawings more in detail, the invention will be fully described.

A base is represented by 2 which is preferably circular in form and has a lower wall 3, an outer peripheral rim or rib 4 and upwardly extending concentrically arranged sleeve supporting ribs 6, 8, 10, 12 and 14. A hollow hub 16 is disposed, as shown. An inner rim or rib 18 extends upwardly from the lower wall as does a dam 20.

Sleeves 22, 24, 26, 28, 30 and 32 extend upwardly from the sleeve supporting rims and, as shown, are perforated in the usual manner as in connection with the innermost sleeve 32.

A cap ring 36 is supported by the central hub 16, a cap ring 38 is supported by the rim 18, and a cap ring 39 is supported by sleeves 24 and 26. A cap 40 is provided on the upper end of the in-

nermost sleeve 32, a cap ring 42 is disposed on the upper ends of the sleeves 28 and 30 and an inclined cap ring 44 is disposed on the upper end of the outermost sleeve 22 which has openings 45 of any desired area.

Fuel inlets 46 and 48 are provided in the bottom wall 3, the former leading into a chamber 50 and the latter leading into a chamber 52. The outer peripheral part 4 and the next adjacent rib 10 form a flame ring or channel 54, the ribs 8 and 10 form a flame channel 56 and the ribs 12 and 14 form a flame channel 58. Wicks of usual form, not shown, are disposed in these channels 54, 56 and 58. The ribs 10 and 12 are spaced apart to form an upwardly extending air passageway 60 and are connected together by spacers 62 which have passageways 64 therethrough. The rim 18 and the rib 8 are spaced apart to form an upwardly extending air passageway 66 therebetween and are connected by connectors 68. Air may flow upwardly through the passageways 60 and 66.

The rib 14 has an opening therethrough which is indicated by 15 and is preferably disposed substantially diametrically opposite to the fuel inlet 46. With the inlet 46 connected to a valved fuel supply when the same is open fuel flows through the inlet 46 and in the direction of arrows a, through the opening 15 into the flame channel 58 and in the operation of the device the central portion of the burner quickly becomes heated so that the fuel is vaporized and air passing upwardly through the central hub 16 and passageway 60 supports combustion in the normal manner.

35. The dam 20 which is disposed between the rib 6 and rim 18 has a passageway 70 therethrough which is preferably diametrically opposite the fuel inlet 48. Adjacent said inlet the rib 6 supporting sleeve 24 extends inwardly and is connected to the dam 20 so as to provide openings 72.

The dam disposed as it is provides in conjunction with rib 6 and rim 18 an inner channel 74 and outer channel 76. Fuel therefor entering inlet flows around through channel 74, through opening 70 around through channel 76 and through openings 72 into the outer flame channel 54 as indicated by arrows b.

The ribs 8 and 10 provide a flame channel 56 which is connected through 64 to an inner flame channel 58 formed between ribs 12 and 14 which in conjunction with inlet 46 and chamber 50 provide an inner system.

This inner system may be used as a unit by admitting fuel into the chamber 50 from whence it flows through 15 to flame channel 58 and thence to flame channel 56.

The rim 4 and rib 6 and channels 74 and 76 provide an outer system wherein the flame channel 54 is outermost. Fuel delivered through 48

takes a circuitous path through channels 74 and 76 to the outermost flame channel 54.

Either system may be operated independently of the other or they may be operated simultaneously and as the base heats up fuel is vaporized and air to support combustion flows upwardly through 16, 60 and 65, the passageway 66 providing air for either one or both of said systems.

The burner may be supported in any desired manner in equipment with which it is to be used and there may be as many burners suitably connected together, as may be desired.

From the above it will be observed that fuel may be delivered through one or both of the fuel inlets to separate chambers from which it passes in a circuitous manner to flame channels and being vaporized it mixes with air for combustion.

The construction is such that an inner system is surrounded by an outer system, each comprising flue inlets, vaporizing chambers and flame channels all to the end that either system may be operated independently of the other or both may be operated simultaneously.

The novel construction facilitates ready and easy control of the heat, efficiency and economy in operation and the construction is such as to make possible the easy cleaning thereof.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A burner for liquid fuel comprising in combination, inner and outer burner systems, said inner system including a lower wall, a central hollow hub extending upwardly from said wall, first and second and third and fourth sleeve supporting ribs extending upwardly from said wall in outwardly sequentially spaced concentric relation, said first and second ribs forming a first flame channel and said third and fourth ribs forming a second flame channel, perforated sleeves extending upwardly from said ribs at the sides of said flame channels, said wall provided with a primary fuel inlet between said hub and said first rib, and second and third ribs spaced apart to form an upwardly extending air passageway, hollow connections between said second and third ribs and provided with openings therethrough whereby fuel may flow from said fuel inlet through said hollow connections to said second flame channel, said outer system including a lower wall and inner and intermediate and outer ribs extending upwardly from said wall and spaced apart and concentrically arranged outside of said inner system, said inner rib being spaced from and supportingly connected to said fourth rib providing an upwardly extending air passageway therebetween, said outer rib and said intermediate rib forming a third flame channel, perforated sleeves extending upwardly from said outer and intermediate ribs, said wall being provided with a secondary fuel inlet between said intermediate and inner ribs, dams extending upwardly between said intermediate and inner ribs having

spaced outer ends providing an opening at a side of said wall opposite said secondary inlet and having inner ends connected to said intermediate rib on opposite sides of said secondary inlet, said intermediate rib having spaced openings adjacent the inner ends of said dams whereby fuel may flow from said secondary inlet around said dams and through the openings in said intermediate ribs into said third flame channel.

10 2. A burner for liquid fuel comprising in combination, inner and outer burner systems, said inner system including a lower wall and a central hollow hub extending upwardly therefrom and first and second and third and fourth sleeve supporting ribs extending upwardly from said wall in outwardly sequentially spaced concentric relation, said first and second ribs forming a first flame channel and said third and fourth ribs forming a second flame channel, perforated sleeves extending upwardly from said ribs at the sides of said flame channels, said wall being provided with a primary fuel inlet between said hub and said first rib, said second and third ribs being spaced apart to form an upwardly extending air passageway and hollow connections between said second and third ribs provided with openings therethrough whereby fuel may flow from said primary inlet through said first flame channel and to said second flame channel through the hollow connections therebetween, said outer system including a lower wall and inner and intermediate and outer ribs extending upwardly from said wall and spaced apart and concentrically arranged outside of said inner system, said inner rib spaced from and supportingly connected to said fourth rib providing an upwardly extending air passageway and said outer and intermediate ribs forming a third flame channel, perforated sleeves extending upwardly from said outer and intermediate ribs, said lower wall being provided with a secondary fuel inlet between said intermediate and inner ribs, dams extending upwardly between said intermediate and inner ribs having spaced outer ends providing an opening at a side of said lower wall opposite said secondary inlet and having inner ends connected to said intermediate rib at opposite sides of said secondary inlet, said intermediate rib having spaced openings adjacent the inner ends of said dams therewith whereby fuel may flow from said secondary inlet around said dams and through the openings in said intermediate ribs into said third flame channel, a cap over the upper end of the sleeve of said first rib, a cap ring extending between said hub and said last mentioned sleeve, a cap ring on the upper ends of the sleeves of said second and third ribs, a cap ring between the sleeves of said fourth and said intermediate ribs, and an annular cap ring supported by the sleeve 60 of said outer rib.
